UNITED STATES PATENT OFFICE.

WILLIAM B. RELTH, OF CHICAGO, ILLINOIS, ASSIGNOR OF NINE-TENTHS TO HENRY G. GUYLE, OF WEST UNION, NEBRASKA.

MULTIPLE TELEPHONE-RECEIVER.

989,191.

Specification of Letters Patent. Patented Apr. 11, 1911.

Application filed August 14, 1905. Serial No. 274,207.

To all whom it may concern:

Be it known that I, WILLIAM B. RELTH, a citizen of the United States, residing at Chicago, in the county of Cook and State of Illinois, have invented a certain new and useful Multiple Telephone-Receiver, of which the following is a specification.

My invention relates to a new article of manufacture in the form of a telephone receiver with connections, and the objects of my improvements are, first, to produce an article whereby a plurality of receivers can be connected to a telephone line and a number of persons can hear the incoming and outgoing messages; second, to provide means whereby the several receivers can readily be connected or disconnected; third, to make a cheap and durable construction; and other objects to become apparent from the description to follow.

Heretofore when several persons desired to hear a conversation or message of any kind transmitted over a telephone line it was accomplished by the aid of a megaphone or the several persons had to remain close to the receiver and remain very quiet. Some of the persons thus listening would often be unable to hear distinctly and sometimes would be unable to understand very important parts of the conversation, as for example when a business meeting was held between persons in different towns or places. By the use of my invention each person who desires to hear the messages transmitted over the telephone line is provided with a separate receiver and for such purposes my invention is indispensable.

To describe my invention so that those versed in the art to which it pertains can make and use the same, I have illustrated it on the accompanying sheet of drawing in which:

Figure 1, is a diagrammatic view showing several receivers embodying my invention connected in a series; Fig. 2, is an enlarged view of my invention, and Fig. 3, is a sectional view of a modified form of a coupling embodied in my invention.

Similar reference characters refer to similar parts throughout the several views.

The receiver 5 is of any construction and

is provided with two exposed electrical contacts, as for instance the binding posts 6, to which the leading out wires 7 are connected. Some distance from the receiver 5 and preferably at their ends the wires 7 are provided with means as the spring clips 8 for readily connecting and disconnecting the same to the exposed electrical contacts, as the posts 6 of another receiver or a telephone instrument. It will be understood that an indefinite number of receivers of this construction may be connected together either in multiple or in series to a telephone line and the messages transmitted over said line can be heard through each of the receivers. To connect the instruments in series as shown in Fig. 1, the spring clips 8 of one receiver are connected to the posts 6 of another receiver.

Instead of the posts 6 on the receiver 5 the spring jack or socket 9 having two contacts insulated from one another may be provided to coöperate with a plug 10 having two contacts connected to the ends of the wires 7.

I am aware that telephone receivers have been made and used long ago, and that they have been connected to another instrument by two wires; and do not claim such a device; but

What I do claim as new and desire to secure by Letters Patent of the United States is:—

1. A telephone attachment comprising spring contact devices for making contact with the terminals of the receiver of a telephone set and thereby temporarily securing said attachment thereto, said spring contact devices made integral and so spaced apart that the two separate connections with the terminals of the receiver are made and broken simultaneously and a telephone receiver conductively connected with said contact devices.

2. A telephone attachment comprising spring contact devices for making contact with the terminals of the receiver of a telephone set and thereby temporarily securing said attachment thereto, and a telephone receiver conductively connected with said contact devices.

3. A telephone attachment comprising
resilient means for making contact with the
terminals of the receiver of a telephone set
and thereby temporarily securing said at-
tachment thereto, and a telephone receiver
conductively connected with said means.
5 In testimony whereof I have signed my

name to this specification in presence of two
subscribing witnesses this 11th day of
March, 1905 at Chicago, Illinois.

WILLIAM B. RELTH.
